LOUD-SPEAKER

Lute P. Wassmann, Chicago, Ill., assignor to Electro-Voice, Incorporated, Buchanan, Mich., a corporation of Indiana

Filed Nov. 21, 1962, Ser. No. 72,573

Term of patent 14 years

(Cl. D26—14)

FIGURE 1 is a side elevational view of a loud-speaker embodying my design, the reverse side being a mirror image;

FIGURE 2 is a front elevational view of the loud-speaker illustrated in FIGURE 1;

FIGURE 3 is a rear elevational view of the loud-speaker of FIGURES 1 and 2;

FIGURE 4 is a side elevational view of the loud-speaker as illustrated in FIGURE 1 partly broken away and in sections; and

FIGURE 5 is a top view of the loud-speaker illustrated

in FIGURES 1 through 4, the bottom view being a mirror image of FIGURE 5.

I claim:

The ornamental design for a loud-speaker, as shown and described.
